UNITED STATES PATENT OFFICE.

CHARLES E. WHITE, OF MOLINE, ILLINOIS, ASSIGNOR TO DEERE & MANSUR COMPANY,
A CORPORATION OF ILLINOIS.

LOCK FOR LEVERS AND THE LIKE.

1,165,477.

Specification of Letters Patent. Patented Dec. 28, 1915.

Original application filed June 14, 1907, Serial No. 378,979. Divided and this application filed April 17, 1911, Serial No. 621,578. Renewed May 18, 1915. Serial No. 29,012.

To all whom it may concern:

Be it known that I, CHARLES E. WHITE, a citizen of the United States, residing at Moline, in the county of Rock Island and State of Illinois, have invented certain new and useful Improvements in Locks for Levers and the like, of which the following is a specification, reference being had therein to the accompanying drawing.

10 This invention relates to locking devices for levers and the like. The invention is applicable to levers of various kinds in various relations and the locking device is also applicable to movable parts of machines or structures other than levers. In the present application I show the invention in connection with a foot lever such as is employed to swing the scrapers of disk harrows. This application, in fact, is a division of my application for disk harrows, filed June 14, 20 1907, Serial No. 378,979, upon which were granted Letters Patent No. 1,020,530. In the present application I show as much of the harrow mechanism as is essential for a 25 clear understanding of the locking device.

The object of the invention is to provide a lock or stop device for levers, and the like, which is simple in construction and convenient to operate.

30 In the drawings, Figure 1 is a plan view of a portion of one of the gangs of disks of a harrow. Fig. 2 is a vertical section taken on the line 2—2 of Fig. 4. Fig. 3 is a fragmentary view showing a detail of the construction. Fig. 4 is a vertical section on the line 4—4 of Fig. 1. Fig. 5 is a view similar to Fig. 4 showing the lever in a different position.

40 Referring in detail to the construction shown, 1 and 2 are parallel bars which are rigidly connected by transverse bars or castings 3, 4 and 5 so as to form a rigid frame.

45 6, 6 are a series of disks suitably mounted upon a spindle 7. The disks are spaced from each other by spools or sleeves 8, 8 and two of these spools are rotatably mounted in bearing boxes 9, 9 which are carried by uprights 10 rigidly secured to the top frame.

50 11 is a square rock shaft rotatably mounted in brackets 12 and 13 carried by the frame bar 2. To this rock shaft are rigidly clamped scrapers 14, 14 which have their lower ends arranged to engage the concave sides of the disks.

15 is a coil spring surrounding the rock 55 shaft 11 and having one end extended upward to engage the frame bar 2 and its other end extended rearward to engage a finger-like extension 16 of the clamp which carries the adjacent scraper 14. This spring tends 60 both to press the scrapers against the disks and to swing the lower ends of the scrapers inward toward the axis of the disks.

17 is a foot lever rigidly connected at one end to the rock shaft 11 and formed at its 65 free end with a suitable foot rest 17^a. Normally the spring 15 holds the scrapers adjacent the axis of the disks, at which time the foot lever is in its uppermost position, but when it is desired to swing the scrapers outward and inward to clean the disks of accumulated soil or trash, the driver, who sits upon a seat at 18, presses downward upon the foot lever to rock the shaft 11 and swing the scrapers outward while the spring serves 70 to return the scrapers when the driver relieves the lever from downward pressure. In the operation of such a disk harrow I have found that it is desirable at times to hold the scrapers in contact with the peripheral parts of the disks, for in some soils it is not necessary to constantly swing the scrapers in order to keep the disks clean. In order to hold the scrapers in such a position, I provide an improved locking device, 80 and it is this locking device to which my invention more especially relates.

19 is an upright pin or bolt which is screwed into a bracket 20 mounted on the lever 17. By turning the bolt 19 it can be 90 adjusted up or down in the bracket and is secured in adjusted position by a nut 21. 22 is a bracket secured to the frame bar 1 at a point adjacent the lever 17 and the bolt 19. This bracket has an aperture 22^a 95 through which the bolt 19 extends. On the front up-turned end 22^b of the bracket is pivoted an oscillating lock or stop 23. This stop has a handle part 23^a and carries on its rear side a rearward extending flat sided 100 flange 23^b. On its front side the stop is formed with a rib 23^c which is designed to engage shoulders 24, 25 on the bracket 22, so as to limit the oscillatory movement of the stop 23 to something less than 90 degrees. 105 The extreme positions of the stop are shown by the full and dotted lines in Fig. 2.

When the stop or lock 23 is in the position

shown in full lines in Fig. 2 it has no effect upon the foot lever 17, because the flange 23^b of the stop is out of the path of the bolt 19, so the latter is free to rise and fall. If, 5 however, the foot lever is pressed to its lowermost position and the stop is then raised to the position shown in dotted lines in Fig. 2, the flange 23^b is thrown across the top or head of the bolt 19 and serves when 10 downward pressure is taken from the foot lever to resist the upward movement of said lever under the action of the spring 15. The face of the flange 23^b is flat and the engaging end of the bolt 19 is also flat so that the 15 upward pressure of the bolt 19 caused by the spring 15 tends to hold the parts in the locking position indicated by dotted lines in Fig. 2.

When it is desired to release the lever 20 from the lock it is not necessary to manually move the lock 23 for by simply pressing downward on the foot lever 17 the head of the bolt 19 is withdrawn from engagement 25 with the flange of the lock and the latter moves under the action of gravity from the position shown in dotted lines of Fig. 2 to the position shown in full lines. This simple gravity release of the stop makes the locking device exceedingly convenient. 30 I have shown my improved lock or stop device in connection with a swinging lever, but it will be readily understood now that it can be used to lock any oscillatory part or member whether it move about an axis 35 or otherwise.

I do not herein claim any of the subject matter covered in the claims in my application Serial No. 670,412, filed Jan. 10, 1912, for improvements in disk harrows, which 40 was also filed as a division of the aforesaid application, Serial No. 378,979, upon which,

as aforesaid, Letters Patent No. 1,020,530 have been issued.

What I claim is:

1. The combination of a lever, a support 45 to which the lever is pivoted, means comprising a spring for moving the lever in one direction, a rod adjustably connected with the lever and a stop pivoted to the support and movable into or out of the path of the 50 rod, one portion of the said stop being enlarged and of sufficient weight to normally hold the stop by the action of gravity out of the path of the rod.

2. The combination of a support and a 55 lever pivoted thereto, means comprising a spring for moving the lever in one direction, a rod connected with the lever, a pivoted stop actuated by gravity to normally lie in lines out of the path of the rod and manually movable into the path of the rod when the lever is moved against the action of the 60 spring to a point near the end of its travel.

3. The combination of a support, a lever pivoted thereto, means comprising a spring 65 for moving the lever in one direction, a rod adjustably connected with the lever, a pivoted stop manually movable to a position abutting against the end of the said rod when the lever is moved against the action 70 of the spring to a point near the end of its travel, the said stop being actuated by gravity to normally lie in a position where it does not interfere with the movement of the rod. 75

In testimony whereof I affix my signature in presence of two witnesses.

CHARLES E. WHITE.
